UNITED STATES PATENT OFFICE.

VITO A. QUAGLIANO, OF EAST BOSTON, MASSACHUSETTS.

WINDOW-SCREEN.

1,171,138.

Specification of Letters Patent.

Patented Feb. 8, 1916.

Application filed July 31, 1914. Serial No. 854,385.

To all whom it may concern:

Be it known that I, VITO A. QUAGLIANO, a subject of the King of Italy, and a resident of East Boston, in the county of Suffolk and State of Massachusetts, have invented a certain new and useful Improvement in Window-Screens, of which the following is a specification, reference being had to the accompanying drawings.

10 The chief object of this invention is to provide simple, inexpensive and efficient means for readily attaching screens to, or for removing them from, ordinary windows, and my said improvement consists mainly 15 of electro-magnetic means for holding such screens in their operative positions in the window frame. Incidentally, I have also improved certain details of construction of such screens and their bracket supports.

20 My said improvement is embodied in the screen shown in the accompanying drawing, Figure 1 being an elevation of a window casing fitted up to receive and support a screen of my improved construction. Figs. 25 2 and 3 are, respectively, reverse and front face views of my improved screen, and Fig. 4 is an edge view of said screen. Fig. 5 is a perspective view of one of several corner brackets, or angle plates, which I provide at the corners of the window casing, and Fig. 6 is a similar view of a bracket provided at or near the vertical center of the window casing, to support the upper portion 30 of the screen when the latter is used with the lower half of the window, and to 35 support the lower portion of said screen when with the upper half of the window, as I will explain in detail later on.

Referring to these drawings, the letter *a* 40 indicates a window casing of ordinary construction, and the letters *b* and *c* indicate, respectively, the upper and lower slideable sash. Fixed in position at the four inner corners of the said casing are angular plates 45 *d* having, preferably, lateral rib or plate portions *d* which may be secured to the casing by screws or otherwise. At the middle of the height of the said casings I secure oppositely disposed horizontal plates *e* which, 50 as here illustrated, are provided with a rib *e'* which may be screwed to the casing, also with a plate *e²* which lies in the same ver-

tical plane as the plates *d* above referred to, all of the described plates being preferably formed of soft (so called "Swedes") iron. 55

The window screen is denoted as a whole by the letter *f*, and it has mounted in each of its four corners thin plates *g* of iron which have been magnetized to such a degree that, when the screen is placed in operative position in the window casing (that is to say, with its plates *g* in contact with the plates *d* and with the plates *e²*), the screen will be held in its operative position by reason of the magnetic adherence (coherence) of the screen plates with the casing plates. When however it is desirable, or necessary, to remove the screen it may be done by forcibly separating the cohering plates; handles *h* for that purpose being secured to the screen at the opposite sides of its frame, as best seen in Figs. 3 and 4 of the drawings. When the screen is used with the lower half of the window, the upper corners of said screen underlie the plates *e* 75 but when the screen is used with the upper half of the window, the lower corners of said screen rest upon said plates *e*.

It will thus be seen that no locks, latches or catches, are required to retain the screen 80 in its operative positions, and as a further advantage, the described magnetic contact of the engaging plates holds the screen frame so close to the window casing or stop bead as to prevent the entrance of flies, mosquitos, and the like pests, and also prevents the rattling of the screen.

While I have particularly described the magnetized plates as mounted upon the screen, it will be obvious that said magnetized plates would be equally efficient if they were secured to the window casing, and the co-operating iron plates were mounted on the screen frame. 90

Having thus described my invention, I 95 claim as new and wish to secure by Letters Patent:—

1. In combination with a window frame, of angular metal plates having ribs for attachment in the corners of the frame, and a 100 screen frame having magnetized plates fixed to its corners adapted to cohere with the plates carried by the window frame.

2. In combination with a window frame,

of angular metal plates having angularly arranged ribs for attachment in each corner of the frame, intermediate plates vertically spaced from the corner plates and fixed to
5 the frame and having horizontal ribs, screen frames having magnetized plates carried by their upper and lower corners and adapted

to cohere with the respective corner plates and intermediate plates.

VITO A. QUAGLIANO.
